UNITED STATES PATENT OFFICE.

ALVIN W. KRAHN, OF MILWAUKEE, WISCONSIN.

COMPUTING-MACHINE.

No. 870,184.

Specification of Letters Patent.

Patented Nov. 5, 1907.

Application filed May 4, 1903. Serial No. 155,518.

To all whom it may concern:

Be it known that I, ALVIN W. KRAHN, a citizen of the United States, residing at Milwaukee, county of Milwaukee, and State of Wisconsin, have invented 5 new and useful Improvements in Computing-Machines, of which the following is a specification.

My invention relates to improvements in computing machines.

The object of my invention is to provide practical 10 and effective mechanism for mechanically solving problems in addition and subtraction and indicating the result visually, also for making and preserving a printed record of the various amounts entering into such problems and the totals thereof, the machine being adapted to receive and compute all the digits constituting a given number simultaneously.

In a former patent issued to Alfred J. Meyer, dated August 27, 1901, and numbered 681,240, certain features similar to those herein described are disclosed, 20 and in some respects the present machine embodies structural improvements upon the mechanism shown in said patent.

In the following description, reference is had to the accompanying drawings in which,

25 Figure 1 is a plan view of the invention, with the casing partially broken away to show the recording mechanism. Fig. 2 is a view, in elevation, of the shifting mechanism of the record sheet holder. Fig. 3 is a vertical longitudinal sectional view. Fig. 4 is a 30 detail view, in plan, of the registering wheels and transferring mechanism. Fig. 5 is a detail rear view of the transferring yokes and their connections. Fig. 6 is a detail side view of the mechanism for communicating motion to one of the registering wheels. Fig. 7 35 is a detail view of the mechanism for manipulating the zero types of the printing mechanism. Fig. 8 is a detail view of the mechanism for operating the inking ribbon. Fig. 9 is a detail view of a portion of the transferring yoke and pawl. Fig. 10 is a detail view 40 of a modified construction used for printing totals. Fig. 11 is a detail of the same, as seen from the front or inner side. Figs. 12 and 13 are detail views of the units and tens wheels respectively drawn on a section line cutting the shaft of the registering wheels in a 45 plane between the transferring cams of the units wheel, and the ratchet of the tens wheel, and showing the transferring mechanism, and a portion of the primary actuating mechanism of said wheels. Fig. 14 is a detail view of one of the registering wheels with its ratchets and cams, a portion of the registering wheel being 50 broken away to show the interior ratchet which is engaged by the stop 32. Fig. 15 is a detail face view of one of the printing segments.

Like parts are identified by the same reference characters throughout the several views.

The machine is provided with an inclined key board

A and vertical stemmed push button keys, arranged in rows and numbered from 1 to 9 in each row, as best shown in Fig. 1. The right hand row represents the units column, and the next row the tens column as 60 usual in such machines.

A registering wheel 10 is provided for each row of keys, the several wheels being mounted on a supporting shaft 11 but turning independently thereof. The periphery of each registering wheel is provided with 65 two successive sets of digits, ranging from 0 to 9 inclusive, and the wheel is rotated from any one of the corresponding row of keys through the medium of the key, push rods 12, elbow levers 13, sliding bar 14, segment carrying lever 15, toothed segment 16, pinion 17, 70 pawl carrying disk 18, pawl 19 and ratchet hub 20, the latter being rigidly connected with the registering wheel. The below levers pertaining to each row of keys are provided with arms graduated in length to correspond with the numerical importance of each 75 key, the difference in the length of each arm being multiplied in the segment lever 15, which is fulcrumed at 22, below its center, and carries the segment 16 upon its longer arm. The lower ends of the elbow lever arms are disconnected from the bars 14, but each bar 80 is provided with a lateral projection 24 located in the path of each lever of its corresponding set, whereby the depression of any one of the keys will actuate the bar independently of the other keys and elbow levers. The bars 14 are retracted by springs 26, and the elbow 85 levers and keys are retracted by springs 27.

As each registering wheel is loose upon the shaft 11 and rotated by pawl and ratchet mechanism, it is desirable to provide a positive stop to limit the rotation of each wheel to the exact distance of key adjustment. 90 To accomplish this result, bars 30, parallel with the bars 14, are each provided with an arm 31, having a catch 32, adapted to be moved into engagement between the teeth of a wheel 33 on the hub 20, the same being normally held out of engagement with such teeth 95 by a spring 35, connecting bar 30 with the frame. The bar 30 is provided with lateral projections 37, one for each elbow lever 13 of the corresponding set, and these projections are arranged to be engaged by the elbow levers during the final key movement, thus pushing 100 the catch 32 between the teeth of wheel 33 and locking the registering wheel against further movement after the completion of a key stroke until the key is retracted sufficiently to permit spring 35 to retract bar 30 to normal position. A dog 38 prevents a backward rotation of the ratchet hub 20 and registering wheel. 105

Automatic transferring mechanism is used to advance each of the registering wheels, (except the unit wheel), step by step from the wheel of next lower value, whenever the latter has registered ten numbers, 110 commencing with the zero or cipher character. This transferring mechanism is arranged to perform the

transferring or carrying operation during the return stroke of the keys, so that it will not interfere with the direct advancement of any or all of the wheels by a simultaneous stroke of keys of different sets. To accomplish this each registering wheel is provided with cam disks 40 and 41,—one such disk being used for each series of digits on the wheel. Each disk 40 is arranged to oscillate a yoke 44 on a cross rod 45 through the medium of a yoke arm 46 in frictional contact with the disk, the yoke being thus oscillated in opposition to a spring 47, connected with an arm 48 of the yoke. Each disk 41 is arranged to operate a similar yoke 50 having arms 46' and 48' and also a spring 47 operating in opposition to the cam. The cam 40 and yoke arm 46 are located in a different plane from the cam 41 and yoke arm 46', so that each cam will actuate but one of the transferring yokes. Two cams 40—41 and corresponding yokes are provided for the reason that the transferring operation is delayed by a trip latch 55 until the return stroke of the keys as hereinafter explained, and therefore if a single cam were employed the addition of a number 9 to a number 9 would not only move the greater radii of the cam into and out of contact with the yoke arm 46, but would rotate the cam to a position for again actuating the arm 46 and prevent the reaction of the yoke at the time of trip latch release. In such case the yoke would of course be kept from actuating the wheel of next higher value. But by providing registering wheels with two sets of digits, and two alternately acting cams, and transferring yoke levers for each wheel, acting in alternation upon the succeeding wheel, it is obvious that neither of the cams can ever occupy a position where it will interfere with the yoke reaction, for the two cams are brought alternately into and out of yoke actuating position for succeeding sets of digits. The yoke 50 is made smaller than the yoke 44 and located within the latter to produce a compact structure. Otherwise the construction of the yoke 50 and its connections is the same as that of the yoke 46 and its connections. Each yoke carries a pawl arm 53, which is adapted to actuate the ratchet hub 20 of the registering wheel of next higher value to that from which such yoke is operated, and sufficient power is stored in the yoke spring 47 during the oscillation of the yoke to advance the higher value registering wheels one step, whenever the yoke arm 46 passes from the long to the short radius of the cam. The spring is, however, held from immediate reaction by a trip latch 55 which engages a catch 56 on the outer portion of the pawl arm 53 and holds the pawl until the final movement of the operating key or keys on the return stroke permits the release of the latch, as explained below.

The trip latches 55 for all the registering wheels are rigidly connected with a frame rod 58, which is journaled in the frame at 59, and each latch is provided with an arm 60 in the path of a lateral projection 61 carried by a corresponding segment lever 15, whereby the registering stroke of any key depresses the corresponding arm 60 through the medium of a projection 61 and oscillates the rod 58 to adjust the latches 55 in position for engagement with the catches 56 of any yoke oscillated by a cam disk sufficiently to bring its catch 56 into position for such engagement. When the key or keys return to normal position, the projec-

tions 61 are withdrawn from their position of engagement with the arms 60 and the latches 55 are then depressed by a spring 64, thus permitting the operation of the pawls of such yokes as have in the meantime been also released by their respective cam disks. 70 The pawls 53 are held in engagement with the ratchet hubs by springs 65.

It will be observed that each pawl arm 53 is extended beyond the catch 56 over an eccentric shaft 67. When the latter is adjusted through the medium of 75 the handle 68, with its greatest radius under the arm 53, the outer end will be elevated in opposition to spring 65 to hold the pawl from the ratchet hub and render the transferring mechanism inoperative. Operations in subtraction can then be performed by depressing keys representing the difference between the number to be subtracted and the next higher number which may be indicated by ciphers for all but the left hand figure. For example, assuming that the registering wheels indicate the number 76 and that it is 80 desired to subtract the number 68 therefrom. The difference between 68 and 100 is 32. The transferring mechanism being rendered inoperative by the shaft 67, the initial registering wheel is advanced two numbers and the tens registering wheel is advanced three 90 numbers in the same manner as if the number 32 were to be added. The indicated result however, will be the numeral 8, for the initial registering wheel will have been advanced from 6 to 8, while the tens registering wheel will have been advanced from 7 to 0 95 without actuating the hundreds wheel as it would do if the carrying mechanism were in its normal operative position. In this application however, I do not claim the transferring and subtracting mechanism, this being made the subject of a separate divisional application, and for the purpose of this application therefore, either the above described mechanism or that shown in the aforesaid patent to A. J. Meyer may be employed.

To secure a printed record, each lever 15 is provided 105 with an arm 70, projecting rearwardly from its fulcrum as a center and carrying a segment 71, containing numerical types. When one of the levers 15 is actuated, the segment 71 is lifted, and the numerical types being spaced to correspond with the differentiation secured 110 by the keys, it will be apparent that types can thus be brought into registry with a platen or printing roller 75 in correspondence with the values of the actuated key. The arms 70 are made to converge, as shown in Fig. 1, in order that the numbers may be compactly printed. 115

The platen 75 and a roller 76 in normal contact therewith are used to support and advance the sheet. An ink ribbon, supported on spools 77 and 78, is interposed between the platen and the segments 71, *i. e.*—between the record sheet held by the platen and the segment 71. 120 When the segment types are in position, an inward movement of the platen will cause an impression of the type to be made upon the record sheet. Such motion is communicated to the platen through the medium of a printing key 80, sliding bars 81 and platen supporting 125 levers 82, the platen being then automatically returned to its normal position by a retracting spring 83, connected with the bar 81.

A ratchet feed is used to advance the record sheet between the printing strokes of the platen. This con- 13

sists of a ratchet wheel 85, connected with roller 76, a pawl actuating lever 86, fulcrumed to the frame, with a spring controlled pawl 87, engaging the wheel 85, and a lug 88 on a lever 82 adapted to impinge on the pawl 5 actuating lever 86, below its fulcrum, during the return stroke of lever 82. In this manner the pawl is actuated to rotate the ratchet wheel and roller 76 step by step.

To hold the segment 71 in its elevated position pending the printing operation, the arm 70 is provided with 10 a toothed bracket segment 90, the teeth of which are engaged by a spring actuated lever pawl 91. This pawl is made to release the bracket after the printing operation by a bar 92 on the bar 81, which engages in a notch 93 in a shoe 94 pivotally carried by the pawl 91 below 15 its fulcrum, whereby the pawl is retracted from the teeth of the bracket. During the printing stroke of the bar 81 the bar 92 is carried past the notch 93 in the shoe to a considerable extent. The initial backward movement of the bars 81 therefore retracts the platen 20 before the cross bar 92 is brought into engagement with the shoe 94. The type segment is thus left in its elevated position until the platen is moved away from it, when the continued backward movement of the bar 81 brings the cross bar 92 into engagement in the notch 25 93 of the shoe 94 and actuates said shoe to release the pawl 91 from the bracket and permit the return of the type segment to normal position by gravity. By thus locating the bar 92 in such a position that it will not 30 actuate the shoe 94 during the initial backward movement of the bar 81, I am enabled to provide for the withdrawal of the platen from contact with the type segment before the latter drops to normal position, and the types will therefore not rub and blur the record sheet during the downward movement of such segment. 35 The final downward movement of the arm 70 brings the lower end of bracket 90 into contact with shoe 94 on the opposite side of the pivot from the notch, and thus lifts the notched end of the shoe to release the bar 92.

It is desirable that the cipher types carried by the 40 segments 71 should not print upon the record sheet at the left of the left hand numeral of value, while those at the right of such numeral should be included in the printing operation. To accomplish this, the cipher types are independently mounted on blocks 96, which 45 are supported from the respective segments 71 by flat springs 97 which normally hold the types out of the line of platen pressure. They are adjusted into printing position by curved levers 98, pivoted to the frame at 99, and actuated from the corresponding arms 70 of 50 the type segments by laterally projecting rollers 100 carried by said arms. The levers 98 are slightly recessed at 101 to receive the rollers when the latter are in normal position, but when the arms 70 are raised, the rollers move out of the recesses 101 and push the 55 levers 98 inwardly to adjust the corresponding cipher types to printing position. Each lever 98 carries an arm 103, which projects laterally along the inner surface of the next lever at the right, whereby the operation of any of the levers 98 causes a simultaneous operation of all similar levers at its right in the direction of cipher type adjustment.

In order that the record sheet may be shifted, a rod 110, upon which the roller 76 is mounted, and which serves as a fulcrum for the levers 82, is mounted to slide 60 longitudinally in the roller and in frame bracket bear-

ings 111, (see Fig. 2), which brackets prevent a longitudinal movement of that roller. The shaft is extended and carries end bars 112 which support the platen 75 and are also connected with a bar 113 on the other side of the rod 110 from that occupied by the platen. The 70 bar 113 is provided with notches 114 in which resilient stops 115 are adapted to engage, the latter being connected with the levers 82 through which the bar 113 is also mounted to slide. With this construction, the record sheet may be manually shifted laterally with 75 the platen whenever a record column is completed. The notches in the bar 113 serve as an index to the lateral adjustment required, and the platen is provided with a knob 116 whereby the sheet may be shifted from one end to the other when a new column of figures 80 is to be started.

In Fig. 8, means are shown for shifting the ink ribbon 120. Each spool shaft is provided with a ratchet wheel 121, and pawls 122, pivoted to levers 123 and 124 respectively, are used to rotate the spools. The levers 85 123 and 124 are each provided with a slot at 125 through which the ribbon passes, and the ribbon is provided with a knot or other suitable projection at 126, near each end, of such size that it will not pass through the slot, but will actuate the lever to push the adjacent pawl into engagement with the teeth of the corresponding ratchet wheel 121. The levers are connected by a link 128, whereby the ratchet engaging movement of one lever disengages the other, and thus reverses the movement of the spools and ink ribbon. 90 129 is a spring, engaging 95 the pawls and holding them resiliently in position for engagement with the ratchet teeth. To actuate the pawls and advance the ratchet teeth step by step, the bars 81 are each provided with a lug 130, (Fig. 3), which engages the rear end of the corresponding pawl to actuate 100 the latter upon its pivot and advance the spool ratchet wheel step by step when in engagement therewith. The ratchet wheels and spool actuating mechanism are located at the base of the machine, while the spools and ribbon are located at a higher point and the 105 slotted ends of the levers bent upwardly to engage the ribbon.

In Fig. 10, I have shown means for printing totals upon the record sheet. Where this is to be done, the arms 70, which support the type segments 71, are not connected 110 positively with the levers 15, but are pivotally connected with the fulcrum shaft 22 and operated from the adjacent levers 15 by hook brackets 132, connected with the levers 15 and arranged to engage underneath the arms 70, thus actuating said arms simultaneously with 115 the movement of the corresponding levers 15 and also permitting an independent adjustment of said arms. To adjust the arms 70 independently, cam wheels 135 are mounted upon the hubs of the registering wheels, and each arranged with graduated radii, corresponding 120 in length with the numerical value of the numerals on the registering wheel from which it is supported. A key 137 is connected to oscillate a rock shaft 139 for printing the totals, and this rock shaft is provided with arms 140 to which levers 141 are pivotally connected. 125 One such lever is provided for each cam wheel, and arranged with its upper end in position to bear on the eccentric periphery of the cam. The throw of the other end of the lever is determined by the length of the radius of the cam wheel at the point of lever contact, the 130

cam serving as a fulcrum for the lever, and as each lever is separately pivoted to an arm 140 of the shaft 139, it is obvious that the throw of each will be governed entirely by the position of the cam.

- 5 Each of the bars 70 is provided with an elbow arm 145 which projects downwardly from the point of attachment to the shaft 22, in the path of the lower end of a corresponding lever 141, whereby, when the latter is actuated, the arms 70 will be lifted to adjust the type 10 segments into a position to expose types for printing which correspond with the numbers on the registering wheel which are simultaneously exposed at the sight opening, and represent the total amount registered. As the throw of each lever is governed entirely by the position of the cam on its corresponding registering wheel, 15 each cam serves as a fulcrum for the lever. It is obvious that the movement of any type segment actuated from the keys 137 will be proportionate to the radius of the corresponding cam wheel 135 at the point of its ful- 20 crum bearing contact with its respective lever 141.

As above stated the radii of the cam wheel at the points of fulcrum bearing contact with the lever are in proportion to the numerical value of the digits on the registering wheel, and it is therefore obvious that with 25 a proper arrangement of the intervening connections, the type segment may be lifted to expose for printing a type of the same value as that indicated at the sight opening for said registering wheel. Therefore, as the numerals exposed in the sight openings of the several 30 registering wheels, represent the total of the amounts registered at any given time, the depression of the key 137 will cause the elevation of each printing segment independently of any movement of the levers 15, and as each segment will be thus lifted to expose for printing 35 a numeral type of the same value as that exposed on the registering wheels, the total amount registered at that time will be printed upon the record sheet.

For resetting the registering wheels 10, the supporting shaft 11 is provided with notches 155 for each registering 40 wheel, and each ratchet hub 20 is provided with an internal spring actuated pawl 156. The pawl is adapted to engage in the notches when the shaft is rotated in the direction of registering wheel advancement. The shaft notches for the several registering wheels are in alignment, and the pawls 156 are in the same relation to the cipher on each registering wheel, so that by turning the shaft until all the pawls have engaged the notches, a uniform adjustment of the registering wheels is secured, and the rotation of the shaft may then be continued until 45 the ciphers are exposed at the usual sight slot 157.

As the registering wheels, in the construction shown, each have two sets of digits, the shaft is provided with two notches 155 for each registering wheel.

Having thus described my invention, what I claim as 55 new and desire to secure by Letters Patent is,—

1. In a machine of the described class, the combination with number carrying devices, differential levers and motion transmitting connections between said levers and the number carrying devices, of a sliding bar provided 60 with a stop adapted to limit the movement of the number carrying devices; lateral projections on said bar in position for engagement by the differentiating levers during their final key stroke movement; and a spring normally holding the bar in a position to render the stop inoperative; said bar being arranged to be actuated by the levers to push the stop into operative position.

2. In a machine of the described class, the combination with number carrying devices, and a set of differentiating levers for each such device, of two parallel sliding bars for each set of said levers, provided with projections in 70 the paths of the levers, and unconnected therewith; and springs arranged to retract said bars; one of said bars having motion transmitting connection with the number carrying device, and being arranged with its projection in position to receive substantially the entire stroke of 75 any corresponding lever; and the other of said bars having a stop for the number carrying device, and being arranged with its projections in position for lever engagement only during the completion of the lever stroke, whereby said stop is held in operative position during a 80 final key stroke movement and an initial retractive movement.

3. In a machine of the described class, the combination of a plurality of registering wheels, each provided with two consecutive sets of peripheral numerals ranging from 85 zero to nine inclusive; independent actuating mechanism for each registering wheel; a cam on each registering wheel for each set of numerals thereon; said cam being graduated in correspondence with the numerical value of the several numerals of the corresponding set; and separate motion transmitting connections for each cam, adapted to communicate motion from such cam to another registering wheel; together with means for detaining such motion transmission during the active movement of said independent actuating mechanism. 90

4. In a machine of the described class, the combination of a plurality of registering wheels, each provided with plural sets of peripheral numerals arranged consecutively and ranging from zero to nine inclusive; Independent 100 actuating connections for each registering wheel; and independent motion transmitting connections for each set of numerals on each wheel; said motion transmitting connections being adapted to communicate motion from one registering wheel to the next; once during each revolution of the corresponding set of numerals; together with trip 105 mechanism adapted to detain the motion transmitting connections when the wheels are being advanced by their independent actuating connections.

5. In a machine of the described class, the combination of a set of registering wheels, means for actuating them 110 independently, a set of independently acting spring operated transferring mechanisms for transmitting step by step motion from one wheel to that of next higher value, a set of cam projections on the transferring wheel, located to rotate in different planes parallel to the wheel, and 115 arranged with each member of the set operatively connected to independently actuate one of the transferring mechanisms in opposition to its actuating spring once during each revolution of the registering wheel,—said registering wheel having consecutive sets of peripheral 120 numerals corresponding with the cam projections and arranged with the numeral of highest value in each set substantially coincident with the highest point on one of the cam projections.

6. In a machine of the described class, the combination 125 with a set of independently revolvable registering wheels, of a cam wheel operatively connected with each registering wheel; an oscillating yoke, having an arm in motion receiving relation to the cam; and devices for communicating motion from said yoke to advance another of said 130 registering wheels step by step; a set of differentiating levers; connections for separately actuating the registering wheels therefrom; and trip mechanism controlled by said connections for detaining the wheel advancing devices of the yokes during the operation of the differentiating levers. 135

7. In a machine of the described class, the combination with registering wheels, differentiating levers, and wheel rotating connections directly operated by the levers,—of a cam wheel connected with each registering wheel; a 140 spring controlled oscillatory member having an arm arranged to receive motion from the cam wheel in opposition to the spring controlling said member; pawl and ratchet mechanism for transmitting the reactionary movement of said member to an adjacent registering wheel; and trip 145

mechanism, controlled by the differentiating levers, to prevent reactionary movements of said oscillatory members during a wheel advancing movement of said levers.

8. In a machine of the described class, the combination 80
5 with registering wheels, differentiating levers, and wheel
rotating connections operated by the levers,—of an oscillatory member adjacent to each registering wheel; connections
10 for moving said member in one direction in correspondence with the rotation of the wheel; member re-
tracting devices operative at fixed intervals of wheel ro-
tation; connections arranged to communicate motion from
15 said member to advance an adjacent registering wheel one
step during the retractive movement of such member; and
devices operated by the differentiating levers, for preventing
a retractive movement of said member during the
wheel advancing movement of said levers.

9. In a machine of the described class, the combination 90
of a set of registering wheels, means for actuating them
independently, a set of independently acting transfer-
20 ring mechanisms for transmitting step by step motion
from one wheel to the next, and a set of cam projections
on the wheel from which the transfer is made, each ar-
ranged to actuate a single transferring mechanism at a
25 different interval from the others, said cam supporting
registering wheel having consecutive sets of peripheral nu-
merals, arranged with the numeral of the highest value in
each set, substantially corresponding in relative position
with the highest point on one of the cam projections.

10. In a machine of the described class, the combina- 100
30 tion of a set of registering wheels, means for actuating
them independently, a set of independently acting trans-
ferring mechanisms for transmitting step by step motion
from one wheel to the next, and a set of cam projections
35 on the wheel from which the transfer is made, each ar-
ranged to actuate a single transferring mechanism at a
different interval from the others, said cam supporting
registering wheel having consecutive sets of peripheral nu-
merals arranged with the numeral of highest value in
40 each set, substantially corresponding in relative position
with the highest point on one of the cam projections, said
cam projections being in different planes.

11. In a device of the described class, a set of register- 110
45 ing wheels each having more than one sequence of per-
ipheral numerals; separate actuating mechanism for
each wheel; a cam wheel for each sequence of numerals;
an oscillatory yoke for each cam wheel, each yoke having
a cam actuated arm and one yoke being located within
50 another; springs arranged to retract said yokes, when the
cam arm bears on the short cam radius; step by step
mechanism for advancing a registering wheel during the
retractive movement of the yoke; together with mechanism
55 controlling the retraction of the yokes and determin-
ing the intervals of such retraction.

12. In a machine of the described class, a set of register- 120
55 ing wheels, segment carrying levers for operating the
same; additional type carrying segments connected with
said levers; catch mechanism for holding the levers in a
position for printing; printing mechanism; and devices
60 connected with the printing mechanism for releasing the
catch mechanism.

13. In a device of the described class, a set of register- 130
65 ing wheels, segment carrying levers for operating the
same; type carrying segments connected with said levers;
catch mechanism for holding the type segments in any
position of printing adjustment; printing mechanism;
70 catch releasing mechanism connected with the printing
mechanism; a record sheet holder and step by step mech-
anism for automatically advancing the sheet in the inter-
vals between the printing strokes.

- 70 14. In a machine of the described class, the combination 140
of printing mechanism; type carrying members; and a re-
silient support for cipher types connected therewith and
normally located outside of the line of printing pressure;
devices for adjusting the members to printing position;
75 and other devices independently supported and coöpera-
tive therewith, for adjusting the cipher type supports into

printing position at the right of the members in printing
position; together with a projection on said adjusting
devices adapted to engage and actuate the cypher type ad-
justing devices.

15. In a machine of the described class, the combination 80
85 of a set of type carrying segments; a printing roller in
operative relation to the segments; means for reciprocating
the printing roller; catch mechanism for holding the
type segments in any desired position of adjustment;
and devices connected with the reciprocating mechanism
of the printing roller for disengaging the catch mechanism,
and permitting the printing segments to return to normal
position.

16. In a machine of the described class, the combina- 90
95 tion with a set of registering wheels and actuating levers
therefor, of a set of type carrying segments operatively
connected with the actuating levers of the registering
wheels; means for locking the segments in any position
to which they may be adjusted by said levers; printing
100 devices in operative relation to said segments; and means,
connected with said printing devices, for releasing the
segments and permitting them to return to normal posi-
tion after the printing operation.

17. In a machine of the described class, the combination 100
105 with a set of registering wheels provided with indicating
numerals; a cam connected with each registering wheel,
with its radii corresponding in length to the value of the
numerals on the registering wheels; a set of printing seg-
ments and a set of key operated levers for actuating said
110 segments,—said cams being arranged to serve as fulcrums
for the respective segment actuating levers, whereby the
throw of said levers is regulated by the cams.

18. In a machine of the described class, the combination 110
115 with a set of registering wheels, of a cam connected with
each registering wheel; a set of adjustable type carrying
segments; a corresponding set of segment adjusting
levers; a set of actuating levers, adapted to communicate
motion respectively to said adjusting levers, and key op-
erated connections therefor,—said cams being arranged to
120 serve as fulcrums for said actuating levers, whereby the
throw of any one of said levers is determined by the posi-
tion of its corresponding cam fulcrum.

19. In a machine of the described class, the combination 120
125 with a set of registering wheels, each having independent
actuating connections, and transferring mechanism com-
prising a graduated member carried by each registering
wheel, a tripping device in operative relation to the gradu-
ated member, and a pawl and ratchet in operative rela-
tion to the tripping device; of a manually actuated mem-
ber, adjustable into and out of the paths of the transfer-
ring pawls, and adapted, in one position of adjustment, to
render the same inoperative.

20. In a machine of the described class, the combina- 130
135 tion of a set of registering wheels, means for actuating them
independently, a set of independently acting transferring
mechanisms for transmitting step by step motion from one
wheel to the next, and a set of cam projections on the
wheel from which the transfer is made, each arranged to
140 actuate a single transferring mechanism at a different in-
terval from the others, said cam supporting registering
wheel having consecutive sets of peripheral numerals, ar-
ranged with the numeral of highest value in each set, sub-
stantially corresponding in relative position with the
highest point on one of the cam projections, together with
means, controlled by the independent wheel actuating
mechanism, for detaining the delivery of a transferring
movement to the next wheel until after the completion of
the active stroke of the independent wheel actuating
mechanism.

In testimony whereof I affix my signature in the presence
of two witnesses.

ALVIN W. KRAHN.
